UNITED STATES PATENT OFFICE.

MARSHALL L. BASSETT, OF WEST HAVEN, CONNECTICUT, ASSIGNOR TO
GEORGE R. KELSEY, OF SAME PLACE.

MACHINE FOR FORMING BLANKS OR ARTICLES FROM WIRE.

SPECIFICATION forming part of Letters Patent No. 323,626, dated August 4, 1885.

Application filed June 25, 1885. (No model.)

To all whom it may concern:

Be it known that I, MARSHALL L. BASSETT, of West Haven, in the county of New Haven and State of Connecticut, have invented a new Improvement in Machines for Forming Blanks or Articles from Wire; and I do hereby declare the following, when taken in connection with accompanying drawings, and the letters of reference marked thereon, to be a full, clear, and exact description of the same, and which said drawings constitute part of this specification, and represent, in—

Figure 1, a top or plan view of so much of a machine for making buckle-frames as is necessary for the illustration of my invention; Fig. 2, a face view of the guiding-block, showing the several openings and the cutters adjacent thereto; Fig. 3, a side view of the feeding-rolls, showing the several annular grooves corresponding to the openings through the guide-block; Fig. 4, a side view, looking toward the bender and former, showing the several wires between them; Fig. 5, a bent buckle-frame.

This invention relates to a device for bending articles made from wire, with special reference to the manufacture of buckle-frames.

In the manufacture of articles from wire a single run of wire is introduced to the machine, cut to the required length and bent, one operation of the machine producing one single article or blank.

The object of my invention is to adapt such machines to the production of several articles simultaneously; and it consists in the combination of several parallel guides, each adapted to receive an independent run of wire, with a feed adapted to act simultaneously upon the several runs of wire so passing through the guides, with a cutter adapted to cut the several runs of wire delivered through said guides, and a bender and former adapted to receive the cut portions of wire and bend them into the required shape, as more fully hereinafter described.

In illustrating my invention I show it as in a machine for bending frames for buckles of that class known as the "Hartshorn" buckle, one of such blanks being shown in Fig. 5 full size.

A represents the guide-block, through which

the wires are to be fed. Longitudinally through this block several openings *a a a a*, (here represented as four,) are formed parallel to each other, each opening adapted to the particular size of wire to be fed to the machine and each adapted to receive an independent run of wire.

B B represent a pair of rolls, having in their periphery annular grooves *b* corresponding to the longitudinal openings through the guide-block A, each pair of grooves being adapted to receive a line of wire between them, and so that by their revolution they will impart an advancing movement to the wire, the revolution of the rolls being toward the guide-block. The movement of these rolls may be constant or intermittent. If intermittent the rotation is to an extent required for the delivery of a single length of wire. If constant they are adapted to slide upon the wire after the given length shall have been delivered, both of such feeding devices being common and well known, except as to the multiple grooves.

On the delivery face of the guide a cutter, C, is arranged to slide toward and from the openings, it being attached to or made a part of a sliding bar, D, to which reciprocating movement is imparted, so that as the cutter advances it will pass over the ends of the several openings through the guide-block, as indicated in broken lines, Fig. 2, and cut off the several projecting wires. *d*, Fig. 1, represents the upper of the several projecting wires.

E is the former, around which the wires so cut are to be bent. It is arranged with its back in the plane of the several wires, as indicated in Figs. 1 and 4. The shape of this former corresponds to the shape of the bends to be made in the wire-blanks.

F is a principal bender, arranged to reciprocate or move forward and back toward and from the former E, as indicated in broken lines, Fig. 1. The wires as they enter pass between the former and the bender, so that when the wires are cut the bender advances, and striking the several wires turns their ends around the former and gives the initial bends, which bends are completed by the side benders G, the former and the several benders being adapted to act together to simultaneously

bend the several blanks of wire delivered and cut, as before described. Thus at a single operation several blanks or articles are bent to the required shape.

5 The former and benders which I have illustrated are the same as in the machines now in use for bending buckle-frames. To the benders a reciprocating movement is imparted toward and from the former. The mechanism 10 for such reciprocating movement is well known and does not require illustration in this application, it having no bearing upon the invention.

I have illustrated the invention as applied 15 to buckle-frames; but it will be understood that the same advantage is attained in making other articles from wire—say, as staples, hooks, eyes, and the numerous articles which are made from wire.

20 By the invention the capacity of a single machine is increased to a very great extent.

I claim—

1. A machine for making articles from wire, consisting in a guide having two or more 25 longitudinal openings in substantially the same plane, through each of which openings an independent run of wire may pass, combined with a feed adapted to simultaneously force the several runs of wire through the

said several openings in the guide-block, a 30 cutter adapted to cut lengths of wire from said several runs so delivered through the several openings in the guide-block, and a former 35 and bender arranged adjacent to the several runs of wire so delivered through the several openings in the guide-block, substantially as described.

2. In a machine for forming buckle-frames, the combination of a guide-block constructed with several longitudinal openings adjacent 40 to and parallel with each other, each of said openings adapted to receive and guide an independent run of wire, a feed adapted to receive several runs of wire and deliver the same to the several said openings in the said guide-block, a cutter arranged to cut lengths or blanks from said several wires so delivered through said several guides, a former, E, in shape corresponding to the frame to be bent, a bender, F, said bender and former arranged 45 to receive the several cut lengths of wire between them, and the supplemental benders G G upon opposite sides of said former, substantially as described.

MARSHALL L. BASSETT.
